UNITED STATES PATENT OFFICE

CHARLES B. SHEPHERD, OF NEW YORK, N. Y., ASSIGNOR TO THE P & M COMPANY, A CORPORATION OF ILLINOIS

RAIL ANCHOR

Application filed March 1, 1930. Serial No. 432,419.

My invention relates to rail anchoring devices adapted to grip a portion of a railroad rail and engage a stationary part of the roadbed to prevent longitudinal creeping 5 movement of said rail.

One of the several objects of the invention is to provide an improved anchor device which may be applied to the base portion of a rail from one side thereof by forcing the 10 anchor device transversely of the rail into gripping engagement with opposite edges of said base. In this connection I aim to provide a one-piece anchor which is so formed as to permit the anchor to be applied to rails 15 having base flanges of different widths and thicknesses without subjecting the flexible portions of the anchor to excessive distortion when the anchor is applied to over-sized rails and at the same time insure a firm spring 20 grip when the anchor is applied to rails of smaller standard size.

Another object is to provide a rail anchor in which the flexible portion of the device is disposed transversely of the anchor and is so 25 proportioned with relation to a relatively rigid part of the anchor that the major portion of the grip of the device is produced by movement of the flexible portion vertically of the relatively rigid portion by forcing the 30 device into gripping engagement with the inclined upper surface of the rail base.

A further object is to provide a one-piece anchor formed to provide a depending tie abutment at one end of the device, which abutment is so formed as to contact with the tie 35 at a substantial distance below the upper surface thereof and also includes the relatively rigid and relatively flexible portions of the anchor.

40 My invention contemplates the arrangement of the rigid and flexible portions in such position relative to each other that the distortion of the flexible portion, during application of the anchor and the tendency 45 which it has to resume the position from which it was sprung, presses the other end of the anchor upwardly and maintains it in locking engagement with the opposite edge of the rail base. In this connection, the rigid 50 and flexible portions of the anchor are so ar-

ranged and proportioned that pressure of the tie abutment downwardly against the ballast of the roadbed will not loosen the resilient grip of the jaw of the anchor on the rail base.

Various other objects of the invention will 55 appear from a detailed description of the two embodiments shown in the drawings, and from the scope and terms of the appended claims.

In the drawings:

Fig. 1 is a side view of a rail anchor constructed in accordance with my invention showing the device applied in its operative position on the base portion of a railroad rail, the full line position of the anchor indicating 60 its normal applied position and the dotted line position indicating the relative position of the flexible part before it is applied to the base flange of the rail.

Fig. 2 is an end view of the anchor shown 70 in Fig. 1 illustrating the manner in which it abuts against the vertical face of the cross tie.

Fig. 3 is a view similar to Fig. 1, but illustrating the anchor in its initial position, that is to say, the position which it assumes before any appreciable transverse pressure is applied to force it to its operative position.

Fig. 4 is a plan view of the anchor, rail base and tie showing one position which the anchor may assume when the cross tie, for any 75 reason, extends diagonally across the base flange of the rail.

Fig. 5 is a side view in elevation of a slightly modified construction illustrating the anchor device applied in its operative position 80 on a rail base.

Referring to the drawings, 10 designates the base portion of a railroad rail and 11 a cross tie or other stationary part of a roadbed on which the rail 10 is supported. The rail 90 anchor, shown in Figs. 1 to 4 inclusive, consists preferably of a body portion 12 which extends across beneath the base of the rail and is formed at one end with a portion 13 for engagement with a vertical edge portion 95 of the rail base at one side of the rail and is formed at the other end with a resilient loop portion adapted to bear against the cross tie 11 and also provides resilient clamping means 100 for gripping the top and bottom surfaces of

the base flange of the rail. The loop portion of the anchor consists, preferably, of a down-turned relatively rigid leg portion 14, the lower end of which is connected, by means of 5 a curved portion 15, to a substantially horizontal portion 15a. The portion 15a merges into the outwardly bowed vertical leg 15b of the loop. The upper portion of the outer leg 15b of the loop is formed with a substantially 10 perpendicular portion 16, arranged opposite the vertical edge 17 of the base flange, and a portion 18 which extends inwardly over the upper surface of the rail base flange and bears against the inclined upper surface 15 thereof. The bearing surface 19 of the jaw 18 is normally spaced from the upper surface of the body 12 a distance less than the thickness of the base flange of the rail, whereby it is necessary to spread apart the surfaces 19 and 20 in applying the anchor to its applied position. Since the leg portion 14 of the loop is relatively rigid, the spreading of the surfaces 19 and 20 results in an upward flexing of the portion 15a and the outwardly 25 bowed portion of the outer leg 15b is straightened slightly, when the clamp end of the anchor is forced to its gripping position. The length of the latter portion 15a may be varied and consequently varies the vertical 30 flexibility of the loop. There is also an outward flexing of the leg 15b of the loop relative to the edge of the rail. The major portion of this outward flexing takes place in the outer leg itself and at the bend 15.

35 Normally the portion 16 and the rigid portion 14 at its juncture with the body 12 are spaced apart so that the lower corner 21 of the rail base will enter the space 22 during the application of the anchor to a rail and 40 thereby avoid excessive flexing of the loop. The bearing surface 20, it will be observed, is located at a point between the end of jaw 18 and the adjacent edge of the rail base. The surface 20, therefore, serves as a ful-

45 crum, about which the body 12 pivots during the movement of the jaw 18 upwardly on the rail base. Consequently the upward pressure on the jaw 18 presses the body firmly against the bottom of the rail and holds the 50 portion 13 in its locking position. The relatively rigid portion 14 takes the major portion of the strain incident to the downward pressure of the loop against the ballast and consequently avoids the tendency which said 55 pressure has to loosen the grip of jaw 18 on the rail.

60 The inward movement of the jaw 18 is resisted by the inclined top surface of the rail base. Normally there is a slight clearance between the inner face 23 and the edge 17 of the base. The transverse spring pressure, resulting from the tendency which the loop has to resume the dotted line position of Fig. 1, exerts a vertical spring grip between the surfaces 19 and 20 and also a transverse

spring grip extending diagonally through the base of the rail from the surface 19 of the jaw to the surface 24 of the locking shoulder.

Under certain conditions the surface 23 of the loop may be moved into gripping contact with the edge 17 of the base flange. Such condition is present when the cross tie extends diagonally across the rail, as shown in Fig. 4, or when, for any reason, the anchor has been shifted to a position similar to that shown in Fig. 4, whereby the rear edge of the surface 23 and the forward edge of the surface 24, having reference to their positions relative to the tie 11, are moved into 70 shackle gripping engagement with the opposite vertical edge portions of the rail base. 75

In applying the anchor to a rail, the jaw 18 is hooked over one base flange of the rail in the position indicated in Fig. 3. The position shown in this figure represents the initial application of the device to a rail, that is to say, before any pressure, or at least any substantial pressure has been applied to force the anchor transversely of the rail. By striking the loop end of the anchor, or by other means, imparting transverse movement of the anchor across the rail base, the jaw 18 will be raised slightly relative to the surface 20. This raising is effected by the upward flexure of the portion 15a, a slight straightening of the outwardly bowed leg 15b, and also by the outward flexing of the leg 15b relative to the edge of the rail, said outward flexing of the leg 15b being produced by reason of the resistance of the frictional contact of the surface 19 upon the inclined surface of the rail. When the anchor has been forced to a position which permits the shoulder 13 to clear the opposite edge of the rail base, the resiliency of the loop portion of the anchor causes the shoulder 13 to move upwardly into engagement with the vertical edge portion of the rail base the spring action of the loop also presses the surfaces 20 and 25 against the bottom surface of the rail. In the drawings I have shown the body portion 12 bearing throughout its length against the bottom surface of the rail base. This construction may be varied by bowing the body portion 12 downwardly so as to confine the engagement with the base flange to the points 20 and 25. 100 105 110 115 120

125 In Fig. 5 I have shown a slightly modified construction. In this modification, the loop portion of the anchor, instead of being provided with an angularly disposed relatively rigid portion 14 as shown in Figs. 1 to 4 inclusive, is made circular, as indicated at 26 in Fig. 5. The portions 16a and the inner portion of the body 12a are spaced apart to provide a space 22a substantially as shown in the preceding figures. The upward movement of jaw 18a relative to the bearing point 20a together with the outward flexing move- 130

ment of the portion 26a, tensions the loop portion of the anchor. In other respects the modified anchor may be and preferably is the same in construction as the anchor illustrated in Figs. 1 to 4 inclusive.

I claim:

1. A rail anchor comprising a body provided at one end with means for engagement with one edge of a rail base and at the other end with a clamp including an inwardly extending jaw bearing against the inclined top surface of the rail base at one side of the rail, a depending vertically flexible portion connected to the jaw, a vertically disposed and relatively rigid portion connected with said vertically flexible portion and bearing against the bottom surface of the rail base at a location intermediate the end of said jaw and the adjacent edge of the rail base, the said rigid and vertically flexible portions being positioned to provide a space between them adapted to receive the lower corner of the base flange during the initial application of the anchor to the rail.

2. A rail anchor comprising a body provided at one end with means for engaging one edge of a rail base and at the other end with a combined tie abutment and clamping loop including an inwardly extending jaw bearing against the inclined top surface of the rail base, a depending outwardly bowed resilient portion connected to the jaw, and a vertically disposed relatively rigid portion bearing against the bottom surface of the rail base at a location beneath the jaw and united with the lower end of said depending portion, the said rigid and resilient portions being positioned to provide a space adapted to receive the lower corner of the base flange embraced during the application of the anchor to a rail.

3. A rail anchor comprising a body formed at one end with a shoulder for engaging the vertical edge portion of one flange of a rail base and at the other end with a resilient clamp for gripping the top and bottom surfaces of the other base flange; said clamp including a relatively rigid leg portion for engagement with the bottom surface of the rail base adjacent one edge thereof and a vertically flexible portion connected with said rigid portion and adapted to normally bear against the top surface of the base flange, the distance between the top bearing of the clamp and the said shoulder, when the anchor is free of the rail, being normally less than the distance between the surfaces of the rail base engaged thereby, whereby distortion of the anchor in its applied position exerts a spring grip diagonally through the base of the rail from said top bearing to said shoulder.

4. A rail anchor comprising a body formed at one end with a shoulder for engaging the vertical edge portion of one base flange of a rail and with an adjacent bearing for engagement with the bottom surface of the rail and

formed at the other end with a resilient clamp for gripping the top and bottom surfaces of the other base flange; said clamp including a relatively rigid leg portion for engagement with the bottom of the rail base adjacent one edge thereof and a vertically flexible portion connected with said rigid leg and adapted to normally bear against the top surface only of the base flange, the distance between the top bearing of the clamp and the said shoulder, when the anchor is free of the rail, being normally less than the distance between the surfaces of the rail engaged thereby, whereby distortion of the anchor in its applied position exerts a spring grip diagonally through the base from said top bearing to said shoulder.

5. A rail anchor for gripping the marginal portions of opposite flanges of a rail base comprising a body portion extending substantially across beneath the rail and formed at one end with a shoulder for engagement with one flange of said rail base and formed at the other end with a substantially circular loop portion providing a tie abutment beneath the edge of the rail engaged thereby, the end of said loop portion terminating in a jaw for engaging the top portion of the rail base flange at a point above the looped end of said body; the distance between the body portion of the anchor and said jaw being normally less than the thickness of the rail base engaged thereby, whereby movement of the anchor to its applied position tensions said loop to exert a resilient clamping action between said jaw and body of the anchor.
